UNITED STATES PATENT OFFICE.

HAROLD W. NICHOLS, OF MAPLEWOOD, NEW JERSEY, ASSIGNOR, BY MESNE ASSIGNMENTS, TO WESTERN ELECTRIC COMPANY, INCORPORATED, A CORPORATION OF NEW YORK.

RADIO TRANSMISSION.

1,422,882.

Specification of Letters Patent. Patented July 18, 1922.

Application filed September 1, 1915, Serial No. 48,452. Renewed January 2, 1920. Serial No. 348,880.

To all whom it may concern:

Be it known that I, HAROLD WILLIAM NICHOLS, a citizen of the United States, residing at Maplewood, in the county of Essex and State of New Jersey, have invented certain new and useful Improvements in Radio Transmission, of which the following is a full, clear, concise, and exact description.

10 This invention relates to the art of transmitting signals by means of high-frequency electrical waves.

Its object is to vary or modulate the amplitude of radiated high-frequency waves 15 in accordance with the wave form of signals to be transmitted. Its object is also to accomplish this modulation without requiring that the telephone transmitter, telegraph key or other primary source of modulated power shall handle all the power required 20 to be modulated.

A further object of this invention is to modulate the radiated power in an efficient manner by correct proportioning of the impedances of the system.

These objects are accomplished by making use of the fact that in a thermionic amplifier of the audion type, the impedance of the output circuit depends upon and varies with the voltage impressed upon the 30 input circuit, and that the changes in power output, due to such changes in impedance, are much larger than the power input required to produce them. On account of this property, it is obvious that if the antenna current is made to flow through the output circuit of an amplifier, large variations in the power radiated from the antenna may be produced without using excessive power in the primary modulating 35 source, and therefore permitting the use of a commercial telephone transmitter or telegraph key as this primary source.

It has been found, however, that the impedance of the output circuit of the vacuum tube amplifier as at present constructed, is so high that it cannot be inserted directly into the antenna without seriously decreasing the current in the antenna and consequently the radiating power of the transmitting system. In order that modulation shall be most efficiently carried out, it is necessary that the impedance of the modulating device shall be comparable with the other impedances in circuit with it, and to

accomplish this correct proportioning of impedances, this invention proposes to insert the vacuum tube as a shunt upon some impedance in the antenna which is comparable with that of the tube. In this way 60 only a fraction, for example one half, of the antenna power is carried by the vacuum tube. For example, in a simple tuned system consisting of an inductance coil and a condenser in series, the impedance between the extreme terminals of this circuit is small, since the system is tuned. On the other hand, the impedance between the two terminals of the coil or that between the two terminals of the condenser, may be made 70 large by sharply tuning the resonant system. In order therefore, to modulate the current in such a system by means of a high impedance modulating device, it would be necessary to connect the high impedance device across the terminals of the coil or the condenser, but not across the extreme terminals of the circuit. In the present invention, therefore, the antenna is tuned 75 as sharply as may be desired for efficient transmission of signals, and the thermionic amplifier is shunted across only a portion of the antenna, said portion having preferably an impedance of the same order of magnitude as that of the amplifier.

80 The exact nature of this invention will be better understood by reference to the drawings, in which Fig. 1 represents one method of matching the impedances concerned; Fig. 2 shows a method of connection in which the effective impedance of an inductance coil is varied; Fig. 3 shows a similar method for varying the effective impedance of a condenser in the antenna circuit; and Fig. 4 shows another method of placing the amplifier effectively in shunt to part of the antenna by using a transformer. In all 85 of these figures the same numerals denote corresponding parts.

90 Referring to Fig. 1, 1—2 is an antenna containing coil 3 and condenser 4 in parallel. 5 is another coil inserted into the antenna and coupled to coil 6, which is supplied with power by means of the high-frequency generator 16, which therefore 95 serves to energize the antenna. The object of using the parallel arrangement 3, 4 of coil and condenser is to secure an impedance of the same order of magnitude as that of the output circuit of the amplifying sys- 110

tem shunting it. 7 is a thermionic repeater of the audion type containing plate 8, grid 9 and filament 10. 11 is a battery or other source of direct current inserted in the output circuit as usual in the operation of such amplifiers. Battery 12 serves to heat the filament 10. It will sometimes be necessary, in order to handle all the power required in the modulating system, to use a plurality of 10 thermionic elements connected in parallel as shown in this figure. 13 is a transformer by means of which variations in voltage caused by microphone 14 are impressed upon the input circuit of the amplifying system. 15 is a battery supplying current to microphone 14.

In the system as shown in this drawing, the effective impedance of the parallel arrangement 3, 4 is varied by the amplifier as 20 discussed in the first part of this specification.

Fig. 2 differs from Fig. 1 only in that the thermionic amplifier is shunted across the coil 5, which is also used in connection 25 with coil 6 and generator 16 to impress power upon the antenna. In the circuit arrangement of this drawing, if the antenna is sharply tuned the impedance of the coil 5 will be comparable with that of the amplifier.

In the arrangement of Fig. 3, modulation is accomplished by placing a variable shunt upon the condenser 4 inserted directly 35 in the antenna circuit. In this figure, in order that the output circuit of the amplifier may be supplied with current, it is necessary to shunt the condenser with the choke coil 17. The impedance of this choke coil to high-frequency currents is so large that 40 practically none of the antenna current passes through it, while at the same time it offers unobstructed passage to direct current in the output circuit of the amplifier. This choke coil also serves another purpose in 45 that it allows the discharge of accumulated electricity on the antenna, such accumulated charges being otherwise prevented from flowing to ground by the condenser 4.

In Fig. 4 this thermionic shunt is placed 50 directly on the generator 16, but since generator and amplifier are coupled to the antenna by transformer 5-6, the effect, for

forced oscillations, is the same as if the parallel arrangement of generator and amplifier (in general with modified impedance) were inserted directly in the antenna. Owing to the fact that this circuit is not so flexible as the others shown, it will not in general be as desirable as one of the others.

Although this invention is described particularly as applying to a wireless transmitting system, it will be understood that the antenna may be replaced by a portion of a wire circuit, for example, a telephone line, 65 without departing from the broad idea underlying this invention. I, therefore, desire not to be limited to a wireless transmitting system, but intend this invention to apply to the use of the modulating apparatus here 70 described in connection with a wire system, as well as with a wireless system.

What is claimed is:

1. In a radio transmission system, an antenna, a source of high-frequency power 75 supplying said antenna, a thermionic discharge path arranged to carry a fraction of the power for said antenna, a source of waves of signaling frequencies, and means for varying the power carried over said 80 thermionic path in accordance with said waves.

2. In a signaling system, an antenna including an impedance element, an electrical discharge device in shunt to said element, 85 said impedance element and said electrical discharge device having impedances of the same order of magnitude, and means in said antenna in series with said element for setting up a high frequency electromotive 90 force in said antenna.

3. A signaling system comprising a transmission circuit, means in said circuit for supplying high frequency current thereto, an impedance element in said circuit in series with said means, and a thermionic element in shunt to said impedance element, 95 said thermionic element and said impedance element having impedances of the same order of magnitude.

In witness whereof, I hereunto subscribe my name this 28th day of August A. D., 1915.

HAROLD W. NICHOLS.
